CLAIM

The ornamental design for the combination cuticle pusher and gel stirrer, as shown and described.

DESCRIPTION

FIG. 1 is a side elevation view of a combination cuticle pusher and gel stirrer showing my new design, the opposite side being identical thereto.

FIG. 2 is a top plan view thereof, the bottom plan view being identical thereto.

FIG. 3 is a front elevation view thereof; and,

FIG. 4 is a rear elevation view thereof.
